[57] CLAIM

The ornamental design for a ribbon cartridge or the like, substantially as shown and described.

DESCRIPTION

FIG. 1 is a perspective view of a ribbon cartridge showing our new design;

FIG. 2 is an enlarged scale front elevational view thereof;

FIG. 3 is a rear elevational view thereof;

FIG. 4 is a left side elevational view thereof;

FIG. 5 is a right side elevational view thereof;

FIG. 6 is a bottom plan view thereof;

FIG. 7 is a top plan view thereof; and

FIG. 8 is a front elevational view of an alternate embodiment of the ribbon cartridge.
